UNITED STATES PATENT OFFICE.

ROYAL E. BALL, OF NEW YORK, N. Y., ASSIGNOR TO THE BALL ELECTRIC COMPANY, OF YONKERS, NEW YORK.

ELECTRIC-ARC LAMP.

SPECIFICATION forming part of Letters Patent No. 674,642, dated May 21, 1901.

Application filed April 11, 1900. Serial No. 12,393. (No model.)

To all whom it may concern:

Be it known that I, ROYAL E. BALL, a citizen of the United States, residing at New York city, borough of Manhattan, county and State of New York, have invented certain new and useful Improvements in Electric-Arc Lamps, of which the following is such a full, clear, and exact description as will enable any one skilled in the art to which it appertains to make and use the same, reference being had to the accompanying drawings, forming part of this specification.

My invention relates to improvements in several different parts of an electric-arc lamp; and my improvements consist in the various novel and peculiar arrangements and combinations of the several parts of the apparatus, all as hereinafter fully described and then pointed out in the claims.

I have illustrated types of my various inventions in the accompanying drawings, wherein—

Figure 1 is a section of my improved lamp, the plane of the section being taken on a vertical plane extending centrally through the lamp, as indicated by line 1 1, Fig. 2. In this view a portion of the arc-inclosing globe is broken away, the telescoping casing is raised in open position, and the outer globe and its holder are omitted. Fig. 2 is an enlarged horizontal section taken at a point just above the tilting frame of the feed-regulating mechanism. Fig. 3 is an enlarged vertical section of the lower guide for the upper carbon, together with a portion of the fixed plate in which the guide is mounted. Fig. 4 is an enlarged side view of the lower portion of the lamp with the vertically-adjustable outer globe and its holder omitted. Fig. 5 is an enlarged vertical sectional view of the lower carbon, the inclosing globe, and the combined carbon-holder and globe-holder. Fig. 6 is an enlarged view of the combined arc-inclosing-globe holder and carbon-holder, the three parts constituting this device being detached from each other. Figs. 7 and 8 are side views of my improved lamp, showing the vertically-adjustable globe with its holder in closed and in open position, respectively. In these two views the combined globe and lower-carbon holder is omitted. Fig. 9 is an enlarged plan

view of one of the adjustable friction-clutches, shown as detached. Fig. 10 is a side view of a portion of the lamp-frame rod and one of the friction-clutches mounted thereon, the 55 clutch being shown partly in vertical section. In this view the clutch shown in full lines indicates the closed position thereof, while the dotted line indicates the open position of the clutch.

Referring to the drawings, in which like numbers of reference designate like parts throughout, 2 and 3 are the upper and lower plates, respectively, of the lamp-frame, and 4 is a casing surrounding the plates, so as to 65 inclose the feed-regulating mechanism for the carbon.

5 is the main magnet.

6 is the shunt which controls the vertically-movable core 7, and 8 is a tilting frame carrying the gearing of the feed-regulating mechanism, the tilting frame being pivoted at 9 and loosely connected at 10 to the core 7, so as to be actuated in the manner well known.

11 is the carbon-rod, the vertical movements 75 of which are controlled by the regulating mechanism, and 12 is the upper carbon carried by such rod.

A fixed tubular casing 13 depends from the under side of the lower plate 3, from which 80 it is completely insulated by a layer of suitable material 14, such as asbestos. This fixed casing 13 has mounted within it a telescoping section 15, the lower end of which is flared outwardly and fits over an annular 85 flange 16, formed upon the upper surface of the base-plate 17 of the lamp. This telescoping casing completely houses the part of the carbon-rod and the upper carbon which lies between the lower plate 3 and the base-plate 90 17. It also, when closed, serves to cover the lower guide and the surrounding parts, so that all such parts are protected against the weather and against the admission thereto of foreign matter. The upper part of the fixed 95 portion of the telescoping casing 13 is provided with ventilating-openings 18 to permit the heated air which may enter the casing to escape, and thus be prevented from reaching the working parts of the lamp, which are located above. When it is desired to gain access to the upper carbon to replace it or for 100

any other reason, the telescoping casing is raised into the full-line position shown in Fig. 1, and it may then be lowered into the dotted-line position to protect the inclosed parts from the weather.

The carbon-rod 11, having the rack 19, which gears with the pinion 20 on the tilting frame 8, is guided solely by a guide 21, which is pivoted at 22 in the tilting frame 8. This form of guide and suspension for the carbon-rod permits it to swing freely, since the rod itself is not guided at any other point. The other guide, which indirectly acts upon the carbon-rod, is a peculiar form of device which 15 co-operates with the upper carbon, as will now be described.

The base-plate 17 of the lamp is formed with a centrally-located circular opening 23, and 24 is a fixed bracket depending from the 20 under side of the base-plate 17, from which it is insulated by a layer of asbestos 25. This bracket 24 is designed to carry the lower-carbon holder and the inner globe 26 which 25 encloses the arc. The upper part of the bracket 24 is formed with a circular opening 27, the walls of which opening are straight or vertical, as shown more particularly in the enlarged view in Fig. 3. The lower guide, which takes 30 within the opening 27, is composed of a comparatively thick and heavy disk 28, having a cylindrical central opening 29 of a diameter considerably larger than the diameter of the carbon 12, which passes through it. This disk 28, which I prefer to make of soapstone, has 35 its periphery 30 formed like the section of a sphere, and its diameter is such that it fits nicely within the cylindrical opening 27 of the fixed piece 24. (See Fig. 3.) This disk 28, in addition to providing a guide for the upper carbon, serves as a cap for the upper end of the inner globe 26, and its weight keeps it seated 40 firmly on the globe. If the upper end of the inner globe should not be perfectly level, the disk 28 readily accommodates itself to the inclination by reason of its rounded periphery 45 30, which permits the disk to tilt readily in any direction out of the horizontal.

To prevent the disk 28 from dropping through the opening 27 when the inner globe 50 26 is removed, I provide the disk with a retaining device 31, which consists in the present construction in a circular plate of a larger diameter than the opening 27, so that the plate overhangs the edges of the disk and will 55 rest upon the fixed piece 24 when the disk is not supported from below by the inner globe. This retaining-plate 31 is formed with a central opening 32 considerably larger than the diameter of the carbon passing through it, 60 and it is secured to the disk by a set of screws 33, which pass through the body of the disk and take into an annular plate 34 on the under side thereof to secure the screws in place. This annular plate 34 is made of a diameter 65 slightly smaller than the inner diameter of the inner globe 26, so that it fits within the mouth of the globe, as shown in Fig. 1.

Upon the disk 28 is mounted a suitably-thick piece of non-combustible flexible material 35. This material is formed with an opening 36 of the same diameter as the carbon which passes through it, so that the soft material fits snugly around the carbon and serves as a guide therefor. In the present construction I place this guide 35, which is a 70 piece of asbestos, between the retaining-plate 31 and the upper face of the disk 28, so that it is clamped firmly in place. By virtue of having the flexible guide 35, which fits snugly around the carbon, of a smaller diameter than the opening 29 in the disk either the disk 75 can be tilted out of the horizontal without disturbing the vertical position of the carbon or the carbon itself can swing or move laterally without being obstructed by the disk, as under such movement the soft material of the guide 35 will readily yield. This asbestos guide 35 acts also as a seal for preventing the heat from the arc reaching the upper part of the lamp, which is an advantage, because in 80 many lamps the heat from the arc has such direct access to the working parts thereof as to impair the same. The fixed bracket 24, depending from the base-plate 17, extends 85 downwardly a considerable distance and at 90 its lower end is formed with a horizontal arm provided with a socket 37, which opens laterally and into which projects a set-screw 38. (See Figs. 1 and 4.) This socket in the bracket is designed to receive my improved 95 combined carbon and globe holder, which comprises a cylindrical tubular member 39, the bore 40 of which is conical or tapering, with the larger end of the taper uppermost, so that the cylindrical lower carbon 41 may 105 be wedged within the holder, as shown in Fig. 5. The upper end of the bore 40 is formed with a bushing or shoulder 42, having cylindrical walls and of a diameter equal to that of the lower carbon, so that the carbon when inserted in the holder is maintained 110 in axial alignment with the bore thereof. This construction insures the perfect centering of the carbon in the holder, and at the same time the carbon may be forced in firmly 115 in the taper of the holder without using any care as to centering it. This feature of the conical receiving-socket for the carbon, combined with the internal shoulder or bushing 120 42, compensates for the ordinary irregularities found in the surface of the carbons, so that the carbon will assume a vertical position when inserted in the holder.

The tubular holder 39 is formed upon its exterior, near its upper end, with an annular 125 rib or flange 43, the under face of which is conical. A screw-thread 44 is formed upon the exterior of the central member 39, and on this thread works a nut 45, which may thus be adjusted along the central member relatively to the flange 43. The flange 43 and the nut 45, which co-operates therewith, are so proportioned that the flange lies within the globe 130 26, while the nut 45 engages the exterior there-

of. In the present construction the upper face of the nut 45 is made flat, so that it abuts against the ground end of the globe 26, as shown in Fig. 5. By this arrangement the globe may be clamped between the flange 43 and the nut 45 by screwing up the latter. However, I prefer to interpose between the engaging face of the flange and the interior of the globe a suitable packing or a washer 46 of soft material, which I preferably make of asbestos. This soft washer permits of the globe being clamped tightly between the two members without the liability of breaking the globe, and, furthermore, it makes a more perfect inclosure, as it affords a better seal than rigid material.

The combined carbon and globe holder being put together with the globe and the carbon mounted therein, as described and as shown in Figs. 4 and 5, is mounted in place in the bracket 24 by inserting the central member 39 laterally in the socket 37 of the bracket and then raising it sufficiently to let the cap 28 rest with its own weight upon the upper end of the globe, whereupon the set-screw 38 is turned down to clamp the holder in the socket. In dismounting the holder from the bracket the set-screw 38 is unscrewed and the holder is lifted out through the open side of the socket 37.

The outer globe 47 for covering the light depends from the lower part of the lamp, being held at its upper end by a suitable holder 48. This holder is vertically adjustable, so that by raising it the outer globe may be carried up against the under side of the base-plate 17, so as to cover the light, as shown in Fig. 7, while lowering the holder causes the globe to descend to a position below the light, as shown in Fig. 8, and in this latter position full access is given to the inner globe and carbon holder for the replacement of the carbons. There are many well-known ways in which this outer globe may be vertically adjusted so as to open and close it; but I show only one way, which consists in two friction-clutches 49 and 50, each of which is formed with a circular opening 51 for receiving the vertical rods 52 and 53, respectively, of the lamp-frame. The opening 51 in each of the clutches is somewhat larger than the frame-rod which passes through it, so that the clutch may be tilted relatively to the rod in order to cause it to bind upon the rod and to release it. The friction-clutch 49 is connected with the holder 48 by a flexible connection or chain 54, while the clutch 50 is likewise connected by a chain 55. By raising the outer end of each of the clutches they are caused to unclutch the rod and may then be moved up or down along the rods, according to whether the outer globe is to be closed or opened. This construction of the vertically-adjustable means for the outer globe-holder affords a very simple and safe means for accomplishing the purpose for which it is designed, and the specific means, as shown, cannot accidentally become de-

tached from the lamp without some part thereof breaking, since the clutches themselves are confined to the lamp-rod 52 and 53 against any accidental detachment therefrom. By using a piece of stone, such as soapstone, for the body of the disk 28 I secure a certain desirable weight for the disk, so that it keeps itself firmly seated upon the upper end of the inclosing globe, and at the same time it provides insulation at this point.

I wish to be understood as not limiting my improvements to the specific forms of construction herewith shown, as various modifications may be made in the same without departing from the spirit of the invention.

Having thus described my invention, what I claim, and desire to secure by Letters Patent, is—

1. The combination of a carbon-rod of an electric-arc lamp, feed-regulating mechanism loosely engaging the said carbon-rod, a guide for said carbon-rod pivoted to a moving part of the feed-regulating mechanism and engaging the carbon-rod at a single point, whereby the carbon-rod is free to swing on the pivot of said guide, substantially as and for the purpose set forth.

2. The combination of a carbon-rod of an electric-arc lamp, feed-regulating mechanism engaging said carbon-rod, a guide pivoted on a moving part of the feed-regulating mechanism and engaging the carbon-rod at a single point and practically where it is engaged by the said feed-regulating mechanism, whereby the carbon-rod is free to swing on the pivot of said guide, substantially as and for the purpose set forth.

3. The combination of a carbon-rod and a tilting feed-regulating mechanism therefor, a guide for said carbon-rod pivoted to the tilting mechanism, the said carbon-rod being free at all other points, and a movable guide for the upper carbon, substantially as and for the purpose set forth.

4. The combination of a carbon-rod provided with a pivoted guide, feed-regulating mechanism for said carbon-rod, and a movable guide for engaging the carbon that is carried by said carbon-rod, substantially as and for the purpose set forth.

5. A movable guide for the upper carbon, the same comprising a disk having a central opening for the carbon, said disk being mounted as to be freely tipped in any direction at an angle to the vertical, substantially as and for the purpose set forth.

6. A movable guide for the upper carbon, the same comprising a horizontal disk having a central perforation for the carbon to pass through, the periphery of said disk being formed like a section of a sphere, a fixed plate having a circular opening with a diameter equal to the diameter of the said disk, and means for retaining the disk within the circular opening at the same time permitting a free rocking movement therein, substantially as and for the purpose set forth.

7. A movable guide for a carbon, the same consisting in a horizontal disk provided with a central opening for the carbon to pass through and mounted so as to tilt in all directions about its vertical axis, the opening in said disk being provided with a soft material for surrounding and engaging the carbon, substantially as and for the purpose set forth.
8. A movable guide for a carbon, the same comprising a disk having the body thereof formed of rigid material provided with a central opening having a larger diameter than the carbon, a piece of flexible material mounted upon said disk and provided with an opening smaller than and concentric with the opening in said disk and adapted to receive the carbon, the said disk being horizontally mounted so as to tilt in all directions about its vertical axis, substantially as and for the purpose set forth.
9. A movable guide for a carbon, the same comprising a fixed plate having a circular opening, a disk of rigid material formed with a central opening for the carbon and having its periphery formed like the section of a sphere and of a diameter slightly less than the diameter of the opening in said fixed plate, a retaining device for preventing the disk from dropping through the opening in the said fixed plate, substantially as and for the purpose set forth.
10. A movable guide for a carbon, the same comprising a fixed plate having a cylindrical opening, a disk provided with a circular opening for the carbon and having its periphery formed like the section of a sphere, the diameter of the disk being slightly less than that of the cylindrical opening in said plate, and means for retaining the disk in the cylindrical opening at the same time permitting it to rock in all directions about its vertical axis, substantially as and for the purpose set forth.
11. A movable guide for a carbon, the same comprising a fixed plate having a circular opening, a disk of rigid material provided with a central opening for the carbon, the said disk having a diameter slightly less than that of the circular opening in the plate so as to fit loosely therein, a plate secured to the upper side of said disk and of a considerably larger diameter than the opening in said plate, a layer of flexible material interposed between the upper face of the disk and the plate secured thereto, the said flexible material being formed with an opening smaller than, but concentric with, the opening in said disk, substantially as and for the purpose set forth.
12. The combination of a carbon-rod and carbon of an electric-arc lamp, an arc-inclosing globe, a tilting horizontal guide-disk mounted so as to tilt in all directions about its vertical axis and through which said carbon loosely passes, said guide-disk adapted to rest loosely upon the upper end of said globe and closing the same, substantially as and for the purpose set forth.
13. A combined carbon-holder and globe-holder consisting in the combination of an externally-threaded tubular member, the socket of which is adapted to receive and hold the carbon, the said tubular member being formed near its upper end with an external flange lying within the globe, a nut mounted upon the thread of said tubular member and adapted to engage with its upper face the end of the globe, and a soft washer interposed between said flange and the interior of the globe, whereby the tightening of the nut exerts an endwise pressure on the globe, clamping it between the nut and the soft washer, substantially as and for the purpose set forth.
14. A tubular carbon-holder for an electric-arc lamp having a tapering socket for receiving the carbon, substantially as and for the purpose set forth.
15. A tubular carbon-holder for an electric-arc lamp having a tapering socket formed at the receiving end of the taper with an internal shoulder, substantially as and for the purpose set forth.
16. The combination of a lamp, a fixed piece and a vertically-adjustable globe-holder adapted to seat itself against the under side of said fixed piece for suspending the globe, one or more rods extending above said fixed piece, and flexible connections having their lower ends attached to said globe-holder and their upper ends provided with clutches traveling on and engaging said rods, substantially as and for the purpose set forth.
17. The combination of a lamp, one or more rods, a fixed piece and a globe-holder adapted to rest against said fixed piece, a clutch mounted on each of said rods and vertically adjustable along the same, said clutch comprising a movable member provided with an opening slightly larger than the said rod which extends through the opening so that depressing one end of said clutch member causes the same to clutch the rod while the raising of said end of the clutch member unclutches said member from the rod, and chain connections between each of the said clutch members and the globe-holder, substantially as and for the purpose set forth.
18. The combination of an upright fixture for a light, a vertically-adjustable globe-holder and a fixed piece against the under side of which the globe-holder is adapted to rest, a set of vertically-adjustable flexible connections attached by their lower ends to said globe-holder and adjustably attached by their upper ends to the upper portion of the fixture, substantially as and for the purpose set forth.
19. The combination of the lower-carbon holder, a depending bracket provided with a horizontal extension having a lateral opening for receiving the carbon-holder, and a set-screw taking into said opening for engaging

said carbon-holder to clamp it in place, substantially as and for the purpose set forth.

20. The combination of a carbon-rod and a tilting feed-regulating mechanism therefor, 5 a guide for said carbon-rod pivoted to the tilting mechanism, an arc-inclosing globe, a combined cap and carbon-guide comprising a disk having a central perforation, said disk being mounted horizontally so as to tilt in all 10 directions about its vertical axis and adapted

to rest upon the upper end of said globe, substantially as and for the purpose set forth.

In testimony whereof I have hereunto set my hand in the presence of the two subscribing witnesses.

ROYAL E. BALL.

Witnesses:

SAMUEL M. CHESNUT,
WILLIS FOWLER.
